UNITED STATES PATENT OFFICE

101,469

DESIGN FOR A HAND STAMP

Louis Melind, Chicago, Ill.

Application August 17, 1935, Serial No. 58,173

Term of patent 14 years

To all whom it may concern:

Be it known that I, Louis Melind, a citizen of the United States, residing at Chicago, in the county of Cook and State of Illinois, have invented a new, original, and ornamental Design for a Hand Stamp, of which the following is a specification, reference being had to the accompanying drawing, forming a part thereof.

Figure 1 is a front elevational view of a hand stamp showing my new design; and

Figure 2 is a side elevational view of the stamp of Figure 1.

In my design the lower front and back horizontal panels, in conjunction with the adjusting

discs extending through slots in the front and back walls of the casing and separating these walls into vertical panels extending upward from adjacent the lower panels, imparts a novel and pleasing appearance to the device as a whole. These features, combined as shown and described, constitute the dominant features of the design of the stamp.

I claim:

The ornamental design for a hand stamp, as shown and described.

In witness whereof, I hereunto subscribe my name this 13th day of August, 1935.

LOUIS MELIND.
